Primary Examiner — Ian Simmons*Assistant Examiner* — Shannon Morgan(74) *Attorney, Agent, or Firm* — Lawrence J. Shurupoff(57) **CLAIM**

The ornamental design for a collapsible funnel, as shown and described.

DESCRIPTION

FIG. 1 is a front perspective view of a collapsible funnel; FIG. 2 is a left side view thereof;

FIG. 3 is a rear view thereof;

FIG. 4 is a right side view thereof;

FIG. 5 is a front view thereof;

FIG. 6 is a top plan view thereof; and,

FIG. 7 is a bottom plan view thereof.

The broken lines in FIGS. 1 and 6 of the collapsible funnel are for the purpose of illustrating environment, and form no part of the claimed design.
